United States Patent Office.

HERMANN VOIGT, OF BUFFALO, NEW YORK.

Letters Patent No. 67,086, dated July 23, 1867.

IMPROVED CURTAIN-FIXTURE.

The Schedule referred to in these Letters Patent and making part of the same.

TO ALL WHOM IT MAY CONCERN:

Be it known that I, HERMANN VOIGT, of the city of Buffalo, in the county of Erie, and State of New York, have invented certain new and useful Improvements in Window-Shade Fixtures; and I do hereby declare that the following is a full and exact description thereof, reference being had to the accompanying drawings, making part of this specification, in which—

Figure 1 is a view of my improvements partially in section attached to the window-frame.

Figures 2 and 3, elevations of the two sides of the lower pulley.

Figure 4 is a horizontal section of the same in plane of line $x\ x$, fig. 2.

Like letters of reference designate corresponding parts in all the figures.

My invention relates to the construction of the lower pulley of window-shade or curtain-fixtures, and to a device for regulating the tension of the roller-cord, as herein specifically set forth.

In the drawings, A A represent portions of one side of the window-casing, to which the shade-roller B, provided with the ordinary fixed pulley C, is suspended in the usual manner. D is the endless-roller cord, which connects the roller-pulley with a small lower pulley, E. This pulley is mounted in the peculiar manner herein-after described in a block or frame, F, formed by bending sheet metal, as shown, or by casting. The tension device consists of a frame or case, G, (preferably of cylindrical form,) which is attached to the window-casing by screws, as shown, or in any other suitable manner, which encloses a small axis, h, which passes loosely through the case and screws into a knob, I, on the outside, by which it is turned. A cord, j, attached to the frame of pulley E, descends through a suitable hole in the upper portion of the case G, and is fastened to the axis h, and wound thereon by turning the knob I, by which the roller-cord D may be tightened or loosened at pleasure. To prevent the force of the tension of the cords from turning the axis and loosening the device, I employ within the case G a friction-disk, l, which is provided with a slot, m, that allows the introduction of the axis, which is recessed at n, on opposite sides, contiguous to the edges of the slot, which fit therein, and prevent the disk turning as well as from sliding on the axis. The shank h is screwed into the knob I, pressing the periphery of the disk against the surface of the case, so that the friction between the two will prevent the axis from turning, except when moved by power applied to the knob. If the friction surfaces become worn the defect is remedied by simply giving the shank a partial turn in the knob. The pulley E is secured in the frame F by means of a semi-cylindrical pin, O, shown most clearly in fig. 4, which represents a plan of the upper, non-bearing, or plane surface. At each end on both sides of this pin are formed notches, p p, cut at right angles with the plane surface for the reception of the sides of the pulley-frame, as shown in fig. 4. There is also a vertical slot, q, made in the end for a purpose presently to be explained. Slotted openings r and r' are formed in the two sides of F, there being left in r' a central rib, s, fig. 2, which acts as a stop by the base of the slot q, in which it fits, striking against it as the pin is inserted, (shown in figs. 2 and 4.) The pin is inserted in the lower and enlarged portion of the opening r in the front side and passed through pulley and r' on the opposite side till its passage is arrested by the stop s, when the pin is slid up in the slots, the edges of the frame F fitting in the notches p, and thereby securely holding it in place, as represented.

The advantages of my improvements are obvious. The tension device, while it is simple of construction, is not liable to get out of repair, and enables the roller-cord to be regulated with the greatest ease whenever required. It also presents a tasty appearance, as the knob, which may be made ornamental, and the cylindrical case are the only parts that are exposed to view. This, contrasted with the distasteful and unreliable appliances in ordinary use, renders its advantages sufficiently manifest.

What I claim as my invention, and desire to secure by Letters Patent, is—

Regulating the tension of the roller-cord by the winding of a cord attached to the lower pulley or bearing thereof around a spindle, substantially as set forth.

I also claim the combination of the knob I, spindle h, and friction-bearing l with the cord j and pulley E, arranged and operating substantially in the manner and for the purpose set forth.

I also claim the axial pin O of pulley E, constructed as described, in combination with the frame F, provided with slotted openings r r' and stop s, arranged and operating with the roller-cord and pulley D C, substantially as and for the purpose specified.

In witness whereof I have hereunto signed my name in the presence of two subscribing witnesses.
